UNITED STATES PATENT OFFICE.

HUBERT A. MYERS, OF TOLEDO, OHIO.

SPARK-PLUG.

1,268,380.

specification of Letters Patent. Patented June 4, 1918.

Application filed May 7, 1917. Serial No. 166,859.

To all whom it may concern:

Be it known that I, HUBERT A. MYERS, a citizen of the United States of America, and resident of Toledo, Lucas county, Ohio, have 5 invented a certain new and useful Improvement in Spark-Plugs, of which the following is a specification.

My invention relates to spark plugs for internal combustion engines.

Generally stated, the object of my invention is to provide novel and improved means for preventing the accumulation of carbon on the inner end-portion of the plug.

A special object is to provide an improved 15 construction and arrangement whereby movable elements, such for example as porcelain balls, are employed for preventing the accumulation of carbon around the inner end of the plug, so that the plug will, so to speak, 20 be self-cleaning in character.

It is also an object to provide certain details and features of construction tending to increase the general efficiency and desirability of a self-cleaning spark plug of this particular construction.

To the foregoing and other useful ends, my invention consists in matters hereinafter set forth and claimed.

In the accompanying drawings:—

Figure 1 is a vertical section of a self-cleaning spark plug embodying the principles of my invention.

Fig. 2 is a horizontal section on line 2—2 in Fig. 1.

As thus illustrated, my invention comprises a bushing or socket-piece A which is screwed into the engine-cylinder in the usual and well-known manner. The porcelain member B can be of any suitable or desired 35 form or construction, but as shown is provided with a shoulder δ which is pressed downward by the screw-threaded packing-nut C, which latter screws into the upper end of the socket-piece A, asbestos packing 40 D being provided around this shoulder to make a tight joint. If desired, a porcelain collar E can be inserted in the lower portion of the socket-piece A, to form a support for the shoulder δ , and for this purpose the 45 lower end of the socket-piece A is provided with a shoulder α to support the lower end

of said collar. The internal diameter of the collar E is greater than the external diameter of the inclosed lower portion of the porcelain B, and the upper and lower ends 55 of said collar are provided with internal flanges e , so that the annular series of balls F is suitably supported in the space f in which they are movable up and down. The lower flange e , it will be seen, constitutes a 60 provision to limit the downward movement of the insulating balls F, and to thus prevent said balls from getting into the path of the spark, the spark gap being formed by stationary means so that the spark gap is 65 always the same. These balls can be of any suitable character, such as porcelain with rough surfaces, and (arranged in this manner) these balls are adapted to be agitated and moved up and down by the explosions 70 and vibrations of the engine, so that they keep the adjacent surface of the porcelain B clean and free from carbon, thereby preventing the inner end of the plug from becoming 75 clogged in the well-known manner of ordinary plugs, with the result that the plug shown and described is practically self-cleaning in character.

The collar E can be omitted, if such is desired, as the balls can be arranged to move 80 up and down between the porcelain B and the inner surface of the socket-piece A, but for some purposes the use of said collar is preferable and desirable. Also, the balls F can be of any suitable shape or size and arranged in any suitable or desired manner, 85 the essential requirement being that they be free to have sufficient movement to enable them to continually rub the porcelain B and thereby prevent the inner end-portion of the 90 plug from filling up with carbon.

The movable balls F, it will be seen, not only keep the adjacent surface of the insulator B free from carbon, but also serve to scour the inner surface of the collar E, so 95 that the space f is prevented from filling up with carbon. Of course, these balls, by contact with each other, and with the surfaces between which they slide up and down, prevent their own surfaces from accumulating 100 carbon thereon. If the ring E is not used, these balls will then move up and down in

direct contact with the inner surface of the metal socket-piece A, and this surface will be kept clean in the same way.

It will be seen that the elements or balls F are so arranged that they are subject to movement by the internal pressure of the engine. When an explosion occurs, the pressure cannot escape into the upper portion of the angular recess f except by passing 5 between the balls, and in this way the pressure will lift the balls and carry them upward until the pressure is equalized at all points in said recess, and then the balls will fall to their lower position. Thus the movable 10 cleaning means is operable by the internal pressure of the engine, so that the required cleaning action will take place even in an engine in which there is very little jarring or vibration. Furthermore, it will be 15 seen that the cleaning means forms no part of the means for producing the sparks, for the electrodes 1 and 2 form the spark gap, and these electrodes are stationary. The electrode 1 is grounded by its rigid connection 20 with the socket piece A, but the electrode 2 is connected in the usual or any manner with the binding post 3 at the upper end of the plug, so that the sparks are produced in the gap between the two electrodes when 25 said binding post is properly connected with the ignition apparatus ordinarily provided for this purpose. The movable cleaning means, however, does not interfere with the 30 sparking means of the plug, for the spark gap is formed by the two stationary electrodes which are located a fixed distance apart. Thus the plug comprises means in 35 addition to the regular or any suitable 40 sparking means, for automatically keeping the spark plug clean, and the cleaning means thus provided is operable by the explosions or internal pressure, as well as by the mere vibration or jolting of the engine, so that the 45 cleaning action will take place even in engines which run smoothly and absolutely without jarring or vibration.

The cleaning means includes, therefore, one or more elements loosely arranged and shaped or formed to roll around and slide 50 and rotate in various directions, on the surface to be kept clean, for each ball F can roll or slide bodily in any direction on said surface, and can rotate about either a horizontal or a vertical axis, or about an oblique 55 axis, during the action of the engine, whereby all portions of said surface are subject to engagement with said cleaning means, and in a way that tends to prevent the ball or balls from becoming wedged or held 60 against movement. When made of porcelain, or any other suitable non-conducting or insulating material, the said ball or balls will not short-circuit the electric current, and cannot form a conducting medium for 65 the current in any way. Moreover, when a

plurality of balls is employed, they turn and rotate in various directions and rub against each other, so that each ball is kept clean and free from carbon, as well as the surface of the plug.

What I claim as my invention is:—

1. A spark plug for internal combustion engines, having movable means operated by the action of the engine and including one or more elements formed to roll around and turn and move bodily in various directions on the surface of the plug, to prevent the accumulation of carbon around the inner end-portion of the plug, and stationary electrodes forming a spark gap and provisions 75 to prevent said means from getting into the path of the spark.

2. The said structure, as specified in claim 1, in which said means comprise an annular series of loose balls disposed above 80 said electrodes and in position to move freely up and down in sliding and rolling contact with the surface to be kept clean, and with each other.

3. In a spark plug, movable means operated by the action of the engine to prevent the accumulation of carbon around the inner end portion of the plug, and a removable cylindric member of insulating material, with an annular space surrounding the 95 inner end-portion of said member, said means comprising a plurality of elements which are movable up and down in said space by the explosions and vibrations of the engine.

4. In a spark plug, movable means operated by the action of the engine to prevent the accumulation of carbon around the inner end portion of the plug, and a cylindric porcelain insulator and a metal socket-piece 105 in which said insulator is held, said means comprising a plurality of cleaning balls which are freely movable up and down in said socket-piece in contact with the cylindric sides of said insulator.

5. In a spark plug, movable means operated by the action of the engine to prevent the accumulation of carbon around the inner end portion of the plug, and a metal socket-piece to be screwed into the cylinder 115 of the engine, with a centrally disposed insulator in said socket-piece, and an insulating collar encircling the lower portion of said insulator, said means comprising a plurality of balls inclosed by said collar and movable freely up and down in contact with said insulator.

6. A spark plug for internal combustion engines, having movable means operable by the internal pressure of the engine and including one or more loose elements shaped to roll around and rotate in various directions on the surface of the plug, and to slide bodily in various directions on said surface, to prevent the accumulation of car- 130

bon around the inner end portion of the plug.

7. A structure as specified in claim 6, said means being movable upward by the internal pressure, in sliding contact with the surface to be cleaned, and movable downward by gravity.

8. In a spark plug, movable means operated by the action of the engine to prevent the accumulation of carbon around the in-

ner end portion of the plug, said means comprising one or more balls loosely arranged to roll around in various directions on the surface to be kept clean, and said plug having electrodes operating independently of 15 said ball or balls to produce the sparking action.

Signed by me at Toledo, Ohio, this 28 day of April 1917.

HUBERT A. MYERS.
